UNITED STATES PATENT OFFICE.

S. LLOYD WIEGAND, OF PHILADELPHIA, PENNSYLVANIA.

CASK-FORMING MACHINE.

SPECIFICATION forming part of Letters Patent No. 437,408, dated September 30, 1890.

Application filed September 12, 1887. Serial No. 249,523. (No model.)

To all whom it may concern:

Be it known that I, S. LLOYD WIEGAND, a citizen of the United States, residing at Philadelphia, in the county of Philadelphia and 5 State of Pennsylvania, have invented certain new and useful Improvements in Cask-Forming Machines; and I do hereby declare the following to be a sufficiently full, clear, and exact description thereof to enable others 10 skilled in the art to make and use the said invention.

This invention relates to the manufacture of casks from staves and heads previously dressed, and has for its object the easy and 15 rapid assembling of the staves with the heads and the securing of the parts together by means of hoops, which may afterward be tightened by a suitable machine, or may be forced on tightly in the machine which is the 20 subject of this invention.

The nature of this invention consists, first, in a mechanism for guiding the staves into a contractible central clamp; second, in a series 25 of such central clamps so arranged that while one is receiving staves another filled with staves may receive the heads and hoops; third, in a mechanism for guiding and conveying the heads into proper position in the cask; fourth, in a mechanism for contracting 30 the ends of the staves upon the heads; fifth, in a mechanism for guiding and placing the end hoops upon the casks; sixth, in the arrangement of mechanism by which the cask as assembled and secured by the end hoops 35 may either while held in the machine receive the other hoops or be discharged from the machine without delaying the other operations in progress automatically in other parts of the machine upon succeeding casks; 40 seventh, in an arrangement of mechanism whereby the casks are automatically discharged from the machine; eighth, in the combination of the several mechanisms hereinbefore stated in one machine, and, ninth, in the 45 construction of the actuating mechanisms for causing the several operations to proceed in proper succession.

I will now proceed to describe this invention particularly, and its mode of operation, 50 referring in so doing to the drawings annexed and the letters of reference marked thereon.

Figure 1 shows a rear elevation of the machine; Fig. 2, an elevation of the right end thereof as shown in Fig. 1; Fig. 3, an elevation of the left end thereof as shown in Fig. 55 1; Fig. 4, a top view or plan thereof; Fig. 5, a front elevation; Fig. 6, a partial section in the plane indicated by the dotted line $z z$ in Figs. 2, 3, and 4; Fig. 7, a partial section in the plane indicated by the dotted line $y y$ in 60 Figs. 2, 3, and 4; Fig. 8, a section in the plane indicated by the dotted line $x x$ in Figs. 1, 4, and 5. Fig. 9 shows in a detached view the intermittently-rotating train of mechanism for placing and holding the staves during 65 the assembling thereof. Fig. 10 shows in a detached view the mechanism for rotating the series of central clamps. Figs. 11 and 11^a show in detached views the mechanism for contracting the end clamps and modifications 70 thereof. Fig. 12 shows in a detached view the mechanism for opening and closing the gap or cleft in the central clamps. Fig. 13 shows in a detached view the mechanism for opening and closing the jaws or segments 75 of the central clamps. Fig. 14 shows in a detached view the mechanism for placing and retracting the gages or fingers for receiving and placing the staves in the central clamps. Fig. 15 shows a modification of the mechanism 80 thereof. Fig. 16 shows in detached view the mechanism for placing and forcing the end hoops on the casks. Figs. 17 and 18 show in side and end views the mechanisms for placing and forcing the intermediate 85 hoops on the cask and for discharging the same from the machine when completed.

The same letters of reference apply to the same parts in the several figures.

A represents the frames of the machine, 90 having strong bolts or braces A' , A^2 , and A^3 passing through them and firmly uniting them. Upon the brace A' is placed a sleeve or hub B, susceptible of rotation thereon and having three arms B' , each containing a circular clamp B^2 , having jaws B^3 , which contract or expand concentrically in each clamp by the action of a series of cams B^4 , operated 95 by a roller B^5 , reciprocated at intervals by a cam B^6 , partially turning to and fro on the 100 sleeve B^2 , such motion being produced partly by the turning of the clamps around the cam

B⁶ and partially by a lever B⁷, worked by a cam B⁸.

The sleeve B, arms B', and clamps B² are rotated through an arc of one hundred and 5 twenty degrees upon the brace A' in the interval of the time between the insertion of the set or series of staves for each cask by a pawl B¹⁵, operating on a wheel B¹⁶ and moved by a lever B²⁴, link B²⁵, and lever B²², operated by a cam B¹⁷ on the shaft E', and is between the intervals of such motion firmly locked by a projection B¹⁸ on a lever B¹⁹, operated by the cam B²⁰, engaging in notches B²¹ in the arms B'.

15 Upon each of the frames A is formed a bearing C concentric with the axes of the foremost one of the clamps B², on which rotates slowly or intermittently a wheel or ring C', bearing a series of arms C², with gages or fingers C³ and C⁴ to receive staves Z, introduced through a cleft or opening B⁹ in the clamp B², with the sides of the staves Z and the croze Y thereof respectively resting upon the gages or fingers C³ and C⁴, so that the several staves 20 Z are received through the cleft B⁹ and conducted in such relative position to each other that when the staves are compressed and sprung together they all fit evenly with the croze Y upon the cask-heads X.

25 The clamps B² are braced across the cleft B⁹ during the closing operation by a hook B¹⁰, hinged to one side of the cleft and engaging in a suitable recess in the opposite side of the cleft, the hook being operated by the cam B¹², 30 turning or reciprocating at intervals on the sleeve B²⁵ with the cam B⁶ through the levers B¹³ and rod B¹⁴.

The staves are introduced through the cleft B⁹ in the clamp B by means of a pair of reciprocating projections or hooks D, operated by levers D', moved by a cam D² on the shaft E, the staves being presented to the hook D by resting them between converging lateral guides D⁷ on supports D⁸ against gages or 45 stops D⁴, which are retracted by a lever D⁵ and cam D⁶ during the movement of the stave by the hooks D. The jaws B⁸, opposite the cleft B⁹, are hinged to permit the staves to pass through the cleft B⁹, as shown in Fig. 11.

50 The arms C² are not rigidly attached to the rings C', but are hinged thereto, as shown in Fig. 14 in a detached view, so that they may be contracted and withdrawn from the staves by means of the rods C⁵ and levers C⁶, operated by a cam C⁷ on the shaft E', thus leaving the assembled staves inclosed and held in the clamp B² free to turn with the clamp B² around the brace A'.

The wheels C' are provided with teeth upon 60 their peripheries, which engage in pinions C⁸ upon a shaft C⁹. The pinions C⁸ engage in wheels C¹² on the shaft E², causing them to turn with equal velocity by means of a star-wheel C¹⁰ receiving intermittent motion from the cam C¹¹ on the shaft E.

As shown in Fig. 15, the mechanism for placing the arms C² and fingers C³ in position

so as to receive and place the staves in the clamp B² and afterward to retract them from the staves when centrally clamped is differently arranged. In this instance the arms C², instead of being hinged or pivotally attached to the ring or wheel C', are made elastic, and the wheels C' fitted so as to slide on the bearing C in the direction of their axis to such a 75 distance as will permit them when retracted to clear the ends of the staves, which is done after the staves have been centrally compressed by the clamp B², the teeth of the wheels C' sliding in or between those of the 80 pinions C⁸. In this retracting operation the sliding motion is imparted to the wheels C' by the bolts C¹³, plates C¹⁴, rods C⁵, levers C⁶, and cam C⁷ on the shaft E'.

F are clamps supported and reciprocated 85 on slides F', secured to the frames A, and provided with jaws F², arranged to open and close by cams F³, operated by levers F⁴ receiving intermittent motion from the cams F⁵ on the shaft E'. The reciprocating motion of the 90 clamps F on the slides F' is produced by rollers F⁶, worked by the cams F⁷ on the shaft E'. The reciprocating motion of the clamps F is for the purpose of retracting them toward the frame A, so that the series of staves assembled in the clamp B² may be brought into concentric position with the clamps F and the clamps F when opened placed around them and after compressing the staves may again be retracted so as to permit the staves held 95 in the clamp B² to pass out and another series in another of the clamps B² to enter and be similarly treated. The jaws F² should be arranged so as to rock or pivotally move on an axis parallel with the circumference of the 100 clamp and adapt themselves to the taper of the cask as it develops in closing the clamp.

The clamps F may be modified and simplified in construction by omitting the jaws F², cams F³, levers F⁴, and cams F⁵ and substituting for them rollers S, as shown in Fig. 11^a, inside of the clamps, which when the clamps F are forced toward the clamps B² by the cams F⁷ press upon the staves and force them inwardly upon the heads. This arrangement 115 is open to the objection that in the event of the staves not being firmly held in the clamp B² they are more liable to be displaced lengthwise.

Concentric with the horizontal axis of the 120 clamps F and resting in brackets or bearings G', attached to the frames A, are splined cylindric spindles G, arranged to both slide and rotate in the bearings G'. The rotative motion is imparted by the pinions G², having 125 keys or feathers G¹², fitting into the splines of the spindles G and receiving rotative motion in both directions from toothed segments G³, reciprocated by cams G⁴ on the shaft E'. The pinions G² are held in position to always 130 engage in the teeth of the segments G³ by means of caps G⁵ holding them against the bearings of the brackets G'. The spindles G have reciprocating sliding motion in the

brackets G' imparted to them by collars G⁶, secured upon them and holding between them collars G⁷, pivotally connected with levers G⁸, operated by cams G⁹ on the shaft E'. Upon 5 the inner ends of the spindles G are formed flat or slightly concave disks G¹⁰, and in the center of each disk is a conical screw-threaded point G¹¹, resembling the point of a gimlet, which points should be of such form and dimensions as to readily and firmly screw into 10 the centers of cask-heads without perforating or splitting them.

Secured to the inner sides of the frames A are grooved racks H, of such dimensions as 15 to receive dressed cask-heads X and permit them to slide in perpendicular plane, so that when resting on the bottom of the racks H the heads X will be concentric with the spindles G. Upon the inner side of the racks H at 20 the lower part the sides of the grooves are cut away sufficiently to permit the heads X to pass toward the center of the machine, and jaws H' are hinged so as to retain the heads X in the grooves, so that the screw-points G¹¹ 25 may be fastened into them. The jaws H' are opened and closed by levers H², worked by cams H³ on the shaft E'. Above the space occupied by the heads X when resting in the bottom of the rack H is a stop H⁴, connected 30 by a lever H⁵ with a similar stop H⁶, placed more than the diameter of a head X above the stop H⁴, which stops move into positions so as to let only one head drop at each reciprocation of the lever H⁵ and to hold the heads 35 X up at all times when the spindles G, disks G¹⁰, and screws G¹¹ are not retracted from the frames H. The levers H⁵ are operated by the cams H³ on the shaft E'.

Concentric with the spindles G and the 40 clamps F are flat rings J, of such dimensions as to readily pass over the cask-heads X and of less internal diameter than the end hoops W of the casks. The rings J are supported on and moved by slides J', passing through guides J² and operated by a cross-head J³, connected 45 by links J⁴ and levers J⁵ with cams J⁶ on the shaft E'. Upon the lower sides of the rings J are formed rims J⁷, which serve to support the hoops W. A series of pins J¹⁴, as shown in 50 dotted lines in Fig. 7, may be substituted for the rims J⁷. Above the rims J⁷, when the rings J are retracted toward the frames A, are grooved guides J⁸, through which hoops may 55 descend and rest on the rims J⁷, the descent of the hoops in the guides J⁸ being controlled by stops J⁹ and J¹⁰, operated by a lever J¹¹, worked by a cam H³, so that one hoop only 60 can descend in each guide J⁸ and that the remaining hoops in the guides J⁸ shall not obstruct the reciprocating motion of the rings J. Springs J¹³ are attached to the rings J so 65 as to bear on each side of the hoops W, so as to retain them in position, the free ends of which springs are curved outwardly, so as to pass readily over the ends of the staves.

Power is applied by a band to the driving pulley K, secured by a friction-clutch L on

the shaft K', and by a pinion K², engaging in a spur-wheel K³. On the shaft K⁴, turning with the wheel K³, is a pinion K⁵, engaging in the spur-wheel K⁶, turning the shaft E', and during the forming of each cask the motion of these three shafts is continuous during the working of the machine. The shaft E and cam C¹¹ are driven with much higher velocity 75 by a pinion K⁷, which gears into a spur-wheel K⁸ on the shaft E. The pinion K⁷ is fitted to turn freely on the shaft K', and upon its side is a clutch K⁹, which engages in a corresponding clutch K¹⁰, splined on the shaft K', and is 80 disengaged automatically by means of the lever K¹¹ and cam K¹² on the shaft E' during the motion of the clamps B² around the brace A' and re-engaged when the motion of the clamps B² ceases. 85

The teeth on the wheel B¹⁶ are of such form that a pinion M on a shaft M' may be readily engaged in it for the purpose of turning it by a hand-wheel or by a crank M², and a large hand-wheel N is placed on the shaft K' for 90 the purpose of turning the machine by hand in adjusting it, and a friction-brake N' is applied to the wheel N, operated by a treadle-lever N², to arrest the motion of the machine promptly in case of accident, the friction-clutch L being also controlled by the same treadle-lever N².

Upon the upper portion of the frames A are secured a hoop-driving mechanism for placing and driving the intermediate hoops between the chines upon the casks. This is 100 preferably done while the cask is in the grasp of the central clamp B².

The completed casks are removed by rollers continuously revolved by the band-wheel O⁸, bands O⁷, band-wheels O⁶, pinion O⁵, spur-wheels O⁴, chains O³, and chain-wheels O², the rollers O being supported in their journals in links O', so that the proper central distances between their axes is maintained for effective transmission of force by the chains O³ and chain-wheels O² and yet permit the upper rollers O to rest upon the cask. The bearings of the lower rollers are made in a rigid frame O⁶. The rollers O are located so 110 that the lower rollers are forward of or in the vertical plane of the axis of the finished cask and the upper rollers but slightly to the rear of such plane. The peripheries of the rollers O project inwardly toward the cask 115 between the claws Q' and Q⁸, for driving the intermediate hoops hereinafter described. The cask as it passes to the highest point of rotation in the clamp B² clears the lower roller O, and passing under the first of the upper 120 rollers lifts it slightly, when the clamp B² opens and releases the cask. Then the cask rests upon the lower rollers, the upper rollers resting upon the cask. The rotary movement of the rollers O draws the cask out of 125 the clamp B² and discharges it upon the inclined plane P. 130

The hoop-driving mechanism consists of a series of cylinders marked Q⁷ and Q⁸, ar-

ranged in circles upon each side of the machine in frames Q⁹ and Q¹⁰, firmly fastened to the frames A of the machine and securely braced together at their upper portions by 5 rods Q¹¹ and Q¹². The central spaces within the circles formed by the cylinders Q⁷ and Q⁸ should be large enough to permit a completed cask to readily pass lengthwise through these spaces. In each of the cylinders Q⁷ and Q⁸ is 10 a piston marked Q⁵ and Q⁶, which is capable of reciprocating motion under pressure of fluids introduced from a reservoir through pipes Q¹³ and controlled and distributed by a valve Q¹⁴ and branched pipes Q¹⁵ and dis- 15 charged by the pipe Q¹⁶. To each of the pistons Q⁵ and Q⁶ is pivotally attached claws Q', Q², Q³, and Q⁴, having shoulders Q¹⁷, adapted to press edgewise against the hoops W', and lips Q¹⁸, adapted to rest against the sides of 20 the hoops W' and support them.

The metal in claws Q', Q², Q³, and Q⁴ should be so proportioned in relation to their pivots as to neither open nor close by gravitation, and have springs Q¹⁹ connected to them so as 25 to close or press them toward each other, and links or chains Q²⁰ connecting with each series of claws to a handle Q²¹, whereby the attendant can open each circle of claws and place the hoops W' within each of them, 30 whereby the reaction of the springs Q¹⁹ pressing the lips Q¹⁸ of the claws against the hoops, they are held therein until forced upon the cask.

The valve Q¹⁴ has a lever Q²² for operating 35 it by the hand of an attendant, so as to control the motion of the pistons and the connected hoop-driving claws. This lever Q²² is connected by a link Q²³ with the lever B¹⁹, so that the valve Q¹⁴ cannot be turned to direct fluid 40 against the pistons in a direction to force them toward the clamp B² when the projection B¹⁸ is disengaged from the clamp B², thus preventing collision of the hoop-driving claws and pistons with the cask during the turning 45 of the clamps B² upon their common axis.

Rings or frames Q²⁴ and Q²⁵ are attached to the pistons Q⁵ and Q⁶, from which links or chains Q²⁶ extend to a lever Q²⁷, one end of which lever is pivotally connected to the lever N², disengaging the clutch L and applying the brake N', and the other end of the lever Q²⁷ is connected with the lever B¹⁹, so that the lever B¹⁹ when lowered so as to disengage the projection B¹⁸ from the notches 50 B²¹ in the arms B' forms a fulcrum for the lever Q²⁷, and the opposite end of the lever Q²⁷ operates the lever N² and disengages the clutch L and applies the brake N' and prevents rotation of the clamps B² and avoids 55 collision of the casks contained therein with the claws Q', Q², Q³, and Q⁴ and pistons Q⁵ and Q⁶ by preventing the turning of the shaft E' with the cam B¹⁷ and the intermediate gearing imparting rotative motion to the 60 clamps B². When the claws Q', Q², Q³, and Q⁴ are retracted, the rings Q²⁴ and Q²⁵ being retracted with them, the chains Q²⁶ change

the position of the lever Q²⁷ so that the lever N² may re-engage the clutch L and release the brake N'. 70

The operation of this machine is as follows: Power being applied to the pulley K and the shaft E put in rotation, heads X are placed in the guides or racks H and hoops W in the racks or guides J⁸. Staves Z, previously planed, 75 crooked cut to length, beveled on the ends, and planed on the joints, are placed successively on supports D³, resting against the stops D⁴. The hooks D draw the staves through the cleft B⁹ into the clamps B², and deposit them on 80 the fingers C³ and C⁴ of the arms C², the wheels C' turning in the bearings C by the action of the pinions C⁸, shaft C⁹, star-wheel C¹⁰, and cam C¹¹. As each stave is introduced at such a distance as to receive the next stave, this 85 operation proceeds until the requisite number of staves has been introduced to form a cask. The further rotation of the shaft E is suspended by the action of the cam K¹² and lever K¹³ disengaging the clutch K¹⁰ from the 90 clutch K⁹. The brace-hook B¹⁰ is then closed over the cleft B⁹ into the recess B¹¹ by the lever B¹³, rod B¹⁴, and cam B¹², operated by the lever B⁷ and cam B⁸ on the shaft E'. The jaws B³ are next closed by the cams B⁴, 95 worked by the lever B⁵ from the cam B⁶, moved by the lever B⁷, operated by the cam B⁸ on the shaft E'. The sleeve B, arms B', and clamps B², bearing the assembled staves now centrally clamped into a circular arch, 100 moves through an arc one hundred and twenty degrees by the action of the ratchet-wheel B¹⁶, pawl B¹⁵, and cam B¹⁷ on the shaft E'. In this position the clamps and connected parts are locked by the projection B¹⁸ on the lever B¹⁹ being engaged and held by the cam B²⁰ 105 on the shaft E' into one of the notches B²¹ in the arms B'. The staves in the clamp B² are thus placed in a central line with the clamps F. Another empty clamp B² is now 110 opposite the wheels C', and the arms C² being again expanded by the action of the cam C⁷, lever C⁶, and rods C⁵, the shaft E resumes its motion by the operation of the cam K¹², lever K¹³, and the clutches K¹⁰ and K⁹. 115 The operation previously described of filling the clamp B² is repeated. At the same time the clamps F slide on their guides F' by the rollers F⁶, worked by the cams F⁷ on the shaft E' over the ends of the staves first clamped 120 far enough to leave exposed a space sufficient to receive the terminal hoops of the cask. The spindles G, meantime having by their rotative action derived from the pinions G², segments G³, and cams G⁴ screwed the points G¹¹ 125 into the heads X, held by the jaws H', so as to secure them in perpendicular position against the disks G¹⁰, thrust the head X into positions opposite the croze in the staves by the operation of the levers G⁸ and cams G⁹, the heads X having been released from the jaws H'. The jaws F² of the clamps F close the staves together upon the heads X, and the cams J⁶, levers J⁵, links J⁴, cross-heads J³, slides 130

J', and rings J drive the hoops W on the ends of the staves Z. The jaws F² are reopened by the action of the cams F³, levers F⁴, and cam F⁵, and are retracted to their original position by the cams F⁷ and rollers F⁶. The rings J are retracted by the further rotation of the cams J⁶ working the levers J⁵, links J⁴, cross-heads J³, and slides J' in opposite directions, and the reverse movement of the spindles G, derived from the cams G⁴, through the segments G³ and pinions G², and the cams G⁹, through the levers G⁸, restore the spindles G to their original position. The cams H³ and lever H² then close the jaws H', and by the action of the lever H⁵ and cams H³ the upper stop H⁶ holds the upper heads X and the lower stop H⁴ drops the lower heads ready to be screwed upon the points G¹¹ for the next cask. As soon as the clamps F, rings J, and spindles G are retracted the cam B²⁰ disengages the projection B¹⁸ on the lever B¹⁹ from the notches B²¹ in the arm B', and the motion of the stave-supplying mechanism, as already described, is again suspended, the hook B¹⁰ fastened, the jaws B³ contracted upon the staves, and the arms C² retracted from the set of staves last introduced, and the clamps B² and connected parts turn through a further arc of one hundred and twenty degrees by the repeated action of the cam B¹⁷, pawl B¹⁵, and ratchet-wheel B¹⁶. The forms of the cams B⁶ and B¹² and their adjustment upon their respective shafts are such that the jaws B³ of the several clamps B² and the hooks B¹⁰, bracing the clefts B⁹, open before the clamps commence to turn and descend after reaching their highest point in rotation, the jaws B³ opening first to release the cask, and the hook B¹⁰ immediately afterward being then relieved of the strain produced by clamping the cask. Immediately after reaching their highest position the casks receive their intermediate hoops from the hoop-driving mechanism Q, in the manner hereinbefore described, and upon the opening of the jaws B³ rest upon and come within the grasp of the rollers O, by which they are passed down the inclined plane P. After the discharge of the cask from the clamp B² the then empty clamp, by rotating through an arc of one hundred and twenty degrees, is presented with its cleft B⁹ at the stave-supports D³ ready to be again filled with staves, as before. These operations are repeated, so that while one set of staves are being introduced another set are receiving the heads and end hoops, and yet a third set receive the intermediate hoops and are discharged ready for the hoop-tightening operations. To more readily discharge the completed casks from the clamp at its highest point of rotation, a series of rotating rollers or wheels O are employed, upon which the casks do not rest until the clamp-jaws B³ open and the wheels pass the cask out lengthwise to an inclined plane P, leading to a hoop-driving ma-

chine for forcing the hoops tightly upon the casks.

Having described this invention, what I claim is—

1. In a machine for erecting casks from dressed staves and heads, the combination of two or more contractible clamps located equidistantly to and arranged to rotate intermittently about a common axis, each clamp having contractible jaws adapted to grasp and compress the bilge of casks, in combination with a pair of contractible and expansible clamps arranged to reciprocate in the direction of their axis and successively surround and compress the ends, the casks held centrally in the intermittently-rotating clamps to permit the application of hoops and insertion of heads, substantially as set forth and described. 70

2. In a machine for erecting casks from dressed staves and heads, the combination of the stave-supports D³, stops D⁴, reciprocating hooks D and cams D² and D⁶ operating them, and retractile stave-supports C², with a series of intermittently-rotating cleft-clamps B², the clamps F, and cams F³ and F⁵ for opening and closing said clamps, constructed and arranged to operate substantially as set forth. 75

3. In a machine for forming casks from dressed staves and heads, the combination of a series of intermittently-rotating clamps B², having clefts B⁹ therein, with the hooks B¹⁰ for bracing said clamps, recesses B¹¹ to engage said hooks with the cams B¹², arms B¹³, and rod B¹⁴, constructed and arranged to open said clefts to receive staves and to brace said clamps during the compression of the staves, substantially as set forth. 80

4. In a machine for forming casks from dressed staves and heads, the combination of the reciprocating hooks D, operated by the levers D' and cam D², stave-supports D³, converging guides D⁷, stops D⁴, operated by the levers D⁵, and the arm D⁶, with the intermittently-rotating and retractile stave-supports C², with the clamps B², having clefts B⁹ adapted to pass staves by the hooks D from the supports D³ to the supports C², as and for the purpose set forth. 85

5. In a machine for forming casks from dressed staves and heads, the combination of the series of intermittently-rotating central clamps B², and mechanism, as described and shown, for placing staves therein, consisting of the hooks D, supports D³, and guides D⁷, with the contractible reciprocating clamps F, head-supporting spindles G, having screws G¹¹ for holding heads, pinions G², segments G³, and cams G⁴, operating said segments, 90 cams G⁹, and levers G, reciprocating said spindles G, for the placing of heads in casks and contracting the staves thereon, substantially as set forth. 95

6. In a machine for forming casks from dressed staves and heads and hoops, the combination of the series of central rotating

clamps B², the mechanism, hereinbefore described and shown, consisting of the hooks D, supports D³, and guides D⁷ for placing staves therein, retractile clamps F, and heads 5 supporting spindles G, with the hoop-driving rings J and their supporting and moving slides J', and mechanism described for reciprocating the slides, constructed and arranged to operate substantially as set forth.

10 7. In a machine for forming casks from dressed staves and heads and hoops, the combination of the stave-compressing clamps B² and F, with the reciprocating head-supporting spindles G, having screw-points G¹¹, with 15 the head-supplying racks H, having jaws H', and cams H³ operating the same, with the stops H⁴ and H⁶, levers H⁵, and cams H⁸, arranged to automatically deliver heads singly, substantially as set forth and shown.

20 8. In a machine for erecting casks from dressed staves and heads, the combination of the reciprocating guided hoop-driving rings J, with the grooved guides J⁸, arranged to receive the hoops W, stops J⁹ and J¹⁰, and 25 connected lever J¹¹, arranged to hold and successively drop the hoops in the path of the rings J, substantially as and for the purpose set forth.

9. In a machine for forming casks from 30 dressed staves and heads and hoops, the combination of the grooved guides J⁸, stops J⁹ and J¹⁰, and lever J¹¹ and cam H⁸ for operating the same, with the reciprocating hoop-driving rings J, moving transversely to the said guides 35 J⁸, and having springs J¹³ in the sides thereof for holding, placing, and forcing the end hoops upon the staves, substantially as set forth and described.

10. In a cask-forming machine, the combination of the rotating clamps B² with the 40 clamps F, spindles G, rings J, and their described respective operating mechanisms, and the intermediate hoop-placing apparatus Q, constructed and arranged substantially as 45 shown, with the rings Q²⁵, connected with the lever Q²⁷ and lever N², as and for the purpose set forth.

11. In a machine for forming casks, the combination of the series of rotating contractible and expansible clamps B², with the stave-feeding mechanism, the head-placing and hoop-placing mechanisms, all as described and shown, and the wheels O and inclined plane P, constructed and arranged to receive 50 the weight of the casks and remove the same upon the expansion of the clamps B² releasing the casks therefrom, substantially as set forth.

12. In a machine for forming casks from 55 dressed staves, the combination of the inter-

mittently-rotating clamps B² with the sleeve B, ratchet-wheel B¹⁶, pawl B¹⁵, and cam B¹⁷, with the lever B¹⁹, having a projection B¹⁸, notches B²¹, and cam B²⁰, constructed and arranged to operate as set forth.

13. In a machine for forming casks, the combination of the stave-feeding mechanism consisting of stave-supports D³, guides D⁷, stops D⁴, and hooks D and cams D² and D⁶, operating the same, the rotating retractile fingers C² for receiving and supporting staves, the series of contractile clamps B², arranged to rotate intermittently about a common axis, the head placing and supporting spindles G, head-supplying racks H, 70 hoop-driving rings J, grooved hoop-guides J⁸, contractile end clamps F, intermediate hoop-driving claws Q', Q², Q³, and Q⁴, pistons Q⁵ and Q⁶, discharging-wheels O, and inclined plane P, with the driving-shaft K', clutches K⁹ 75 and K¹⁰, lever K¹², shaft E', and bearing cams B⁸, B¹⁷, B²⁰, C⁷, F⁵, F⁷, G⁴, G⁹, H³, H⁷, J⁶, J¹², and K¹³, constructed and arranged to simultaneously place and grasp staves in one clamp B², place heads in staves and compress and bind 80 with hoops the staves in another clamp upon heads, and place the intermediate hoops upon casks in another clamp, and discharge casks thus hooped, and provide intermissions of the several working parts during the turning motion of the clamps, substantially as and for 85 the purpose set forth.

14. In a machine for forming casks, the combination of the stave-feeding mechanism consisting of stave-supports D³, guides D⁷, 90 stops D⁴, and hooks D and cams D² and D⁶, operating the same, the rotating retractile fingers C² for receiving and supporting staves, the series of contractile clamps B², arranged to rotate intermittently about a 95 common axis, the head placing and supporting spindles D, head-supplying racks H, hoop-driving rings J, grooved hoop-guides J⁸, contractile end clamps F, discharging-wheels O, and inclined plane P, with the driving-shaft 100 K', clutches K⁹ and K¹⁰, lever K¹², shaft E', and bearing cams B⁸, B¹⁷, B²⁰, C⁷, F⁵, F⁷, G⁴, G⁹, H³, H⁷, J⁶, J¹², and K¹³, constructed and arranged to simultaneously place and grasp staves in 105 one clamp B², place heads in staves and compress and bind with hoops the staves in another clamp upon heads and discharge casks thus hooped from another clamp, and provide intermissions of the several working parts during the turning motion of the clamps, 110 substantially as and for the purpose set forth.

S. LLOYD WIEGAND.
